US00D816216S

(12) **United States Design Patent** (10) **Patent No.:** **US D816,216 S**
(45) **Date of Patent:** **** Apr. 24, 2018**

(54) **CONNECTOR**

(71) Applicant: **Fisher & Paykel Healthcare Limited**,
Auckland (NZ)

(72) Inventors: **Laurence Gulliver**, Auckland (NZ);
Michael Paul Ronayne, Auckland (NZ); **Charles William Douglas**
Irving, Auckland (NZ); **Mark Thomas O'Connor**, Auckland (NZ)

(73) Assignee: **Fisher & Paykel Healthcare Limited**
(NZ)

(**) Term: **15 Years**

(21) Appl. No.: **29/551,020**

(22) Filed: **Jan. 8, 2016**

Related U.S. Application Data

(63) Continuation of application No. 29/429,467, filed on
Aug. 10, 2012, now Pat. No. Des. 747,471.
